UNITED STATES PATENT OFFICE

GEORGE G. MEVI, OF NEW YORK, N. Y.

LOOSE LEAF BINDER

Application filed September 4, 1930. Serial No. 479,776.

It is old in the looseleaf binder art to fasten the leaves removably in position within the binder through the medium of an appropriate number of binder posts or screws which extend through the leaves adjacent the rear edges of the latter and through front and rear strips between which the said portions of the leaves are arranged. In these binders the leaves are held through the cooperative action of said strips and binder posts or screws and said strips are hingedly connected along corresponding longitudinal edges to the back member of the binder cover to permit the binder to be opened at any leaf. Moreover, it is common in such binders to so correlate the leaf fastening elements as to permit the removal of selected leaves and whenever the occasion demands it the replacement of said leaves in the binder and also to permit additional leaves to be inserted at selected places within the binder whenever desired. Various constructions having this purpose in view have been proposed.

The instant invention primarily relates to the provision of correlated binder posts or screws and locking elements which will cooperate with each other and with the strips between which the rear edges of the leaves are arranged in securing said edges against accidental displacement while permitting removal of a selected leaf or leaves from the binder and the insertion of a leaf or leaves into the binder at any desired place or places in the latter.

More particularly defined, this invention includes a post and a locking element relatively so formed and arranged that when in place within the binder said post will project from one of the strips and into the other strip—through any leaves intermediate the strips—and its upper end will be releasably engaged with the locking element at places above and below the last mentioned strip. Still more particularly defined the construction includes a post and a locking element, said post having its end opposite the locking element secured to one of the strips and said locking element being pivoted to the other strip and formed with an opening into which an edge of the latter strip projects and with

spaced members adapted respectively to engage the post at places above and below said strip when in locking relationship with the post.

In other words, this invention comprises a looseleaf binder whose leaves are removably secured through the medium of binding elements including front and rear strips hingedly mounted within the binder, an appropriate number of posts each of which has one of its ends secured to one of said strips and its opposite end extending into an opening in the other strip, and an appropriate number of locking elements which are pivotally secured to the latter strip and each formed to include upper and lower members to engage the corresponding post at places above and below said latter strip: and wherein the post and locking element are relatively so formed that the engagement between them will be effective to prevent accidental displacement of the post and strip while at the same time such engagement will be of a nature to permit the ready release of the post and strip from each other whenever such release is desired.

The invention also consists in certain improvements of a detail nature in the construction of the post, these improvements having relation, respectively, to provision for longitudinal extension of the post, to the manner in which the post is secured to one strip by the locking element at one end and to the manner in which its opposite end is secured to the other strip.

Typical embodiments of the invention are illustrated in the accompanying drawings wherein like characters of reference denote corresponding parts in the several figures. In said drawings:

Fig. 1 is a plan view of a binder constructed in accordance with my invention, showing one of the cover members of the binder in open position and the binding elements in their locked and unlocked relationship in full and dotted outlines, respectively; this figure also illustrating in dotted lines the cut-out portions in the under members of the locking elements to receive corresponding parts of the posts, respectively;

Fig. 2 is a detail section, as on the line 2—2 of Fig. 1 on a larger scale than the latter figure and intended more clearly to illustrate the correlation of the binding strips, bound leaves, binder posts and locking elements in the locked position of the parts;

Fig. 3 is a detail representation illustrative of the correlation of the parts when in the positions they occupy to permit insertion or removal of leaves;

Fig. 4 is a sectional detail representation of a slightly different construction of post adapted to be riveted to the back strip, also shown in said figure;

Fig. 5 is a detail sectional representation showing still another form of post and also showing its connection to the back strip and its correlation with the front strip and with the locking element when the latter is in locking position;

Fig. 6 is a detail representation of a locking element particularly adapted for use with the construction of posts shown in Figs. 2 and 4, the said element being viewed from the under side; and

Fig. 7 is a detail representation of a locking element, viewed from the upper side, particularly adapted for use with the construction of post shown in Fig. 5.

Referring first to Figs. 1, 2 and 3 of the drawings: A and B designate the front and rear cover-members, connected with each other by a flexible back C; and D and E respectively designate the front and rear strips between which the rear longitudinal edges of the leaves F are bound. The said strips are hingedly connected along their corresponding longitudinal edges, as along the lines 10, to the back member C to permit the opening of the book at any leaf of the latter.

The leaves F are held in their proper positions with relation to the strips D and E through the medium of correlated posts and locking elements hereinafter described in detail.

Different typical embodiments of the posts are illustrated. Before entering upon a description of the details of the several posts, it may be stated that in each instance each post is appropriately secured at its inner end to the rear strip, E, and extend thence through openings in the leaves F and into openings in the front strip D and in each instance each post also is formed to provide a shoulder immediately below the lower surface of the strip D, to be engaged by a member of the corresponding fastening element, and each preferably terminates with its outer end substantially flush with the outer surface of said strip D, so as to be covered by another member of said fastening element, when the parts are in locked-together relationship.

Thus it will be noticed that in the construction shown best in Fig. 2 the post G comprises a body member 11 and a member 12

formed integral with and projecting from one end of said body member and formed with a shoulder 13 which is arranged intermediate the length of the member 12. The upper end portion 12^a of said member 12 extends into an opening in the strip D and the shoulder 13 engages the under surface of said strip and is spaced from the upper end of said body 11. The lower end of the body 11 rests upon the upper surface of the strip E and is formed with an internally threaded socket 14 to receive a screw 15 which extends through said strip and has its head 16 engaged with the under surface thereof. The post G is thus removably clamped at its lower end to the strip E. The screw is of such length as to permit adjustment of the length of the post to accord with the number and thickness of the leaves within the binder, merely by relative rotation of the screw 15 and body.

In the construction shown in Fig. 4 the upper end 12' of the body 11 of the post, marked G', instead of being integral with said body is of separate formation and is screwed into a socket 14' formed in the upper end of the body, being threaded as shown at 15' for said purpose. The lower end of the body 11' of this post, instead of being secured to the lower strip, E, in a manner which permits its ready removal therefrom, is riveted, as shown at 16', to the under surface of said strip. The member 12' is formed with a shoulder 13' which is spaced from the threaded portion 15' and from the upper terminal portion, 13^a, of said member. In the use of this particular embodiment of post as a part of a looseleaf binder, the upper end 13^a of the member 12' will extend into the upper strip D (not shown in this figure) and the shoulder 13' will be immediately beneath said strip, as explained with relation to the form shown in Fig. 2.

The particular form of post shown in Fig. 5, and marked G'' comprises a body 11'' whose lower end extends through the lower strip E and is formed with an integral head 16'' to engage the lower surface of said strip. The screw, marked 12'' in this particular form, has the lower end of its shank threaded into a socket formed in the upper end of the body. The upper end of this screw 12'' is in the form of a head 13'' which is disposed in an opening in the upper strip D and terminates substantially flush with the outer surface of said strip. The lower end of this head provides a shoulder, 13^a, corresponding to the shoulders 13 and 13' of Figs. 2 and 4, respectively.

It will thus be seen that these several forms of posts have the following common characteristics; each comprises a plurality of members having relative adjustment permitting longitudinal extension of the post to accommodate greater or lesser numbers of leaves

and each includes means at one end of its body member to secure it to one of the strips, and a member at its other end to extend into an opening in the other strip, and a shoulder 5 above the upper end of its body member and suitably adjacent the under surface of the latter strip; to be engaged by a member of a locking element to be now described.

Two forms of this locking element are 10 exemplified, which although slightly differing from each other in minute details are alike in principle. The form of locking element marked H in Fig. 1, is preferred for use with the posts shown in Figs. 2, 3 and 4. This locking element is of substantially U-shape in cross section and is carried by the strip D, to which it is pivoted at one of its ends, as shown at h, Fig. 1. Being substantially U-shaped in cross section, it comprises two 15 spaced limbs 20 and 21 connected with each other along their corresponding longitudinal edges by a member 22. When attached to the strip D the limb 20 will overlie and the limb 21 will underlie the opposite surfaces of said 20 strip and the connecting member 22 will be alongside the free longitudinal edge of said strip. The under limb 21 of the locking element is formed with a cut-away portion 24 to receive the corresponding part of the members 12, 12' or 12'' of the posts G, G' or G'', as the case may be. The shoulder, 13 or 13', according to which form of the invention is 25 employed, rests upon the portion of said member 21 adjacent its cut-away portion 24 while the member 20 of the locking element extends over the opening in the strip D into which the upper end of the post projects when the parts are in their locked-together relationship. It will be apparent that the parts may 30 be thus locked together or unlocked from each other merely by turning the locking element upon its pivot at h, in which operation movement of the locking element in one direction will engage it with the post at a point below 35 the strip and also substantially at a place above said strip, and movement in the opposite direction will free it from its engagement with the post. When the post has been thus freed the strip D may be turned back pivotally, along the line 10, in order that any one 40 or more leaves bound within the binder may be removed or other leaves may be placed in the binder.

The construction of lock shown in Figs. 5 and 7, marked H' in said figures is applicable to the posts illustrated in Figs. 1, 2, 3 and 4, but is more particularly designed for use in relation to the construction shown in Fig. 5. It does not differ in principle from the locking element H. The only respects in which it differs in detail from said locking element H, except in size, it being of somewhat heavier construction than said element H, is that its lower limb, marked 21', is shorter from 45 the connecting section, marked 22' to its free

edge than the distance between the free edge of the limb 20' and said section 22', and that it has a bent-up projection 25 to be engaged by the thumb nail of the user, for example, for convenience in unlocking it. The said 70 lower limb 21' has an opening 24' in its edge to receive the shank 12'' of the screw at a place immediately beneath the shoulder 132 when the parts are in their locked relationship, at which time the part 25 of the upper 75 limb 20' overlies the head 13'' of said screw, as shown in Fig. 5.

It will be understood that although the drawings illustrate and the foregoing description sets forth the correlation of the 80 parts in which the locking elements are attached to the upper strip, D, this being the preferred arrangement, yet it would not be a departure from the spirit of the invention to reverse the position of the posts and attach the locking elements to the under strip, E, and hence the terms "front", "rear", "upper", "under", "above", "underlie", "overlie", etc., wherever used in this specification, including 85 the claims, are intended to be construed as illustrative merely and not restrictively. Other changes in the details also may be made without departing from the spirit of the invention as defined by appended claims. 90

Having thus described the invention, what 95 I believe to be new and desire to secure by Letters Patent, is:—

1. A loose leaf binder, including a post adapted to extend through the leaves and having a fastening means at one end and a 100 shoulder adjacent its other end, and a locking element pivoted at one end and having spaced members projecting from its pivoted end and arranged to overlie the upper extremity of the post and underlie said shoulder, respectively. 105

2. In a loose leaf binder, a post adapted to extend through the leaves and having a shoulder near one end, and a pivoted locking element having spaced members one of which is 110 formed with an open-ended slot to receive the portion of the post adjacent said shoulder, the other member of said lock being adapted to project over the extremity of the post.

3. In a loose leaf binder, a post adapted to 115 extend through the leaves and including a body member and an end member of lesser diameter than the body member, said end member formed to provide a shoulder spaced from the end of the body member, and a pivoted locking element having spaced members one of which is formed with an open-ended slot to receive the portion of the post which is of lesser diameter and to underlie said shoulder, the other member of said locking 120 element being adapted to overlie the end of the post provided with the shoulder. 125

4. A loose leaf binder comprising a cover, a post, means by which the post is hingedly attached at one end to the cover, said post 130

adapted to extend through the leaves and having a shoulder adjacent its other end, and a strip hingedly connected with the cover and provided with a pivoted element having a member which underlies the strip and engages the post at a place adjacent said shoulder and locks the corresponding end of the post detachably to said strip.

5. In a loose leaf binder, a cover, spaced strips hingedly secured along corresponding longitudinal edges within the cover, a post having one of its ends attached to one of the strips and its other end adapted to extend into an opening in the other strip and having a shoulder adjacent the under surface of the latter, and a locking element pivoted at one end to the latter strip and formed with inner and outer members one of which is adapted to overlie the corresponding terminal of the post and the other to underlie said shoulder, when the parts are in locked relationship.

10 6. A structure according to claim 4 where-
in the post is of lesser diameter adjacent the shoulder and the member of the locking ele-
25 ment which underlies the shoulder has an opening in its edge to receive said portion of the post having the lesser diameter.

15 7. In a loose leaf binder, a cover, spaced strips hingedly secured along corresponding longitudinal edges within the cover, a lon-
30 gitudinally extensible post including a body member and a screw having threaded engage-
35 ment with the body member at one end of the latter, said post having one of its ends ex-
tending through and attached to one of said strips and its other end adapted to extend into the other strip and provided with a shoulder adjacent the under surface of the latter strip, and a locking element pivoted to the latter strip and including spaced mem-
40 bers which overlie the end of the post within the strip and underlie the shoulder adja-
45 cent said strip, respectively.

45 In testimony wherof I affix my signature.
GEORGE G. MEVI.
